John M. Eddleman, Fort Worth, Tex., and
Geraldine Van Cleave Phillips, Denver, Colo.

Application August 20, 1949, Serial No. 4,632

Term of patent 14 years

(Cl. D86—10)

To all whom it may concern:

Be it known that we, John M. Eddleman and Geraldine Van Cleave Phillips, citizens of the United States of America, residing at Fort Worth, in the county of Tarrant and State of Texas, and Denver, in the county of Denver and State of Colorado, have invented a new, original, and ornamental Design for an Auto Vanity Case, of which the following is a specification, reference being had to the accompanying drawing, forming part thereof.

Figure 1 is a perspective view of an auto vanity case, showing our new design, and illustrating the same with the lid raised.

We claim:

The ornamental design for an auto vanity case, substantially as shown.

JOHN M. EDDLEMAN.
GERALDINE VAN CLEAVE PHILLIPS.
